UNITED STATES PATENT OFFICE.

FLORENCE C. WASHBURN, OF NORWICH, NEW YORK.

CLOTHES-LINE COVER.

1,287,535.

Specification of Letters Patent. Patented Dec. 10, 1918.

Application filed June 9, 1917. Serial No. 173,846.

To all whom it may concern:

Be it known that I, FLORENCE C. WASHBURN, a citizen of the United States, residing at Norwich, in the county of Chenango 5 and State of New York, have invented certain new and useful Improvements in Clothes-Line Covers, of which the following is a specification.

This invention has relation to a laundry 10 accessory, and has for an object to provide means for covering a clothes line whereby clothes may be fastened thereto, without contacting with the clothes line proper, thereby preventing the clothes from becoming soiled.

Another object of the invention is to provide a device for covering clothes lines in the 15 form of a strip of fabric or the like and a container therefor in the nature of a spring operated reel whereby to contain the cover 20 within a confined space when not in use.

A still further object of the invention is to provide a clothes line cover having the above named characteristics, and means for creasing the cover while the same is being 25 wound upon the reel to thereby bring the surfaces of the cover which have been in contact with the clothes line together, to prevent soiling of the other side of the cover by contact with the inside of the cover, 30 which would occur were it not for the provision of this means.

In addition to the foregoing my invention comprehends improvements in the details of construction and arrangement of the parts 35 to be hereinafter more fully described and particularly set forth in the appended claims.

In the accompanying drawings in which similar and corresponding parts are designated by the same characters of reference 40 throughout the several views in which they appear. Figure 1, is a view in side elevation of my device illustrating the same in use.

Fig. 2, is a view of the device in edge elevation and

Fig. 3, is a view in section taken on the line 3—3 of Fig. 2.

With reference to the drawings, 10 indicates the container or casing of the device, said casing comprising spaced disks 11 connected by an annular wall 12 forming in effect a flat cylindrical casing as illustrated.

A handle structure designated as an entirety at 13 is provided for the container, and comprises a plate 14 secured to the exterior face of one of the members 11 and positioned radially thereon with one extremity projecting beyond the periphery of the disk and formed with extensions 15 which are curved to form a portion of a hinge joint which coacts with another member 16. Said member 16 is in 60 the form of a plate corresponding in width to the width of the plate 14 and bent at right angles to provide a portion 17 and a portion 18. The portion 17 is formed upon one end with a lug for positioning between 65 the extensions 15 of the plate 14 whereby a pintle inserted through said extensions and said lug, may connect the plates 16 and 14 for relative movement. The member 18 is formed upon its extremity with a longitudinally extending slot 19 whereby when said member is disposed against the face of the disk member 11 opposite to the member carrying the plate 14, a turn button 20 on the first mentioned disk member may enter said 70 slot 19 to secure the handle structure to the container. A handle 21 is secured to the portion 17 of the plate 16. A reel structure within the container is provided and comprises a pintle 22 which is disposed centrally within the container and extended 75 transversely thereof, and is held therein by means of screws 23 which penetrate both disk 11 centrally thereof and also the ends of the pintle to secure the pintle in place and 80 against rotation relative to the casing. A drum 24 is disposed within the casing, and a coil spring 25 is inclosed within the drum and encircled about the pintle with its inner end secured to the pintle and its outer end 90 to the interior surface of the drum as indicated in Fig. 3. A tongue 26 is struck up from the surface of the drum to enter an opening 27 formed in one end of the clothes line cover indicated at 28. The clothes line 95 cover 28 is in the nature of a strip of fabric of standard length and when not in use is designed to be wound upon the drum and entirely housed within the container. The opposite end of the cover is provided with 100 a ring 29 to permit the cover to be withdrawn from the container when desired.

The annular wall 12 of the casing is formed with a transversely extending elongated opening 30 which is rounded at one end as indicated at 31. An extension 32 extends into the opening 30 from a point opposite the rounded end 31 of the opening as indicated in Fig. 2, the end of the extension being spaced from the rounded end of the opening as indicated.

- 10 In use, the outer end of the cover is withdrawn partly from the casing and secured to the clothes line by means of a clothes pin or other fastening in a manner to cover the upper surface of the clothes line. It will be noted that the annular wall 12 is spaced inwardly from the periphery of the disk members 11 sufficiently to permit the clothes line to pass between the annular wall of the casing and the portion 17 of the handle structure as indicated in Fig. 2. Therefore, to unwind the cover, it is but necessary to grasp the handle and move the device along the clothes line away from the point of fastening of the cover to the line.
- 15 20 25 The clothes may then be suspended upon the line and owing to the provision of the cover contact of the clothes line with the clothes will be absolutely obviated.

As the cover is unwound, the spring 25 within the drum is placed under strain whereby to rewind the cover on the drum when the device is disengaged from the clothes line. It will be obvious that owing to the provision of the extension 32 within the opening 30 through which opening the cover passes when being withdrawn from the container or wound up therein, a longitudinally extending crease is formed in the cover throughout its length thereby bringing the surface of the cover which contacted with the clothes line on the inside of the crease, and permitting that portion of the cover which contacted with the clothes to be in contact as the cover is wound up. In this manner, should the inner surface of the cover become soiled by contact with the clothes line, the outer surface of the cover will not become soiled by contact with the inside of the cover which would take place were it not for the doubling of the cover in the manner explained above. Therefore, the cover may be used and reused several times without possibility of soiling the clothing before it becomes necessary to clean the cover or substitute a new one in place of the old one.

While I have illustrated and described my invention with some degree of particularity, I realize that in practice various alterations thereover may be made, and I therefore desire to reserve the right and privilege of changing the form of the details of construction, or otherwise altering the arrangement of the correlated parts

without departing from the spirit of the invention, or the scope of the appended claims.

Having thus described my invention what I claim as new and desire to secure by Letters Patent is:—

1. A clothes line cover including a strip 70 of flexible material, adapted to be laid upon the upper surface of a clothes line in contiguous relation thereto, carrying means for said strip when removed from the line, and means carried by said strip carrying means 75 for folding said strip.

2. A clothes line cover including a strip 80 of flexible material adapted to be laid upon the upper surface of a clothes line and in contiguous relation thereto, a reel upon which the cover may be wound when not in use, and means for folding said strip to prevent contact of the line contacting face thereof with its opposite face when wound upon the reel.

3. A clothes line cover including a strip 85 of flexible material, a container, a reel mounted within the container for rotation upon which the cover may be wound when not in use, and handle for said container 90 adapted to receive the clothes line between the container and the handle, and means preventing contact of the opposite face of the strip when wound or unwound with respect to the reel.

4. A clothes line cover, including a strip 95 of flexible material, a container, a reel mounted within the container around which the strip may be wound when not in use, a spring acting upon the reel and adapted to 100 be placed under strain when the cover is unwound whereby the cover may be automatically wound upon the reel when the spring is released, a handle carried by the container adapted to straddle the clothes 105 line when said container is supported thereon and means carried by the container for folding the strip as wound and permitting the same to be spread upon the line when unwound.

5. A clothes line covering device including a strip of flexible material, a container, a handle structure including a handle, and a substantially U-shaped member secured thereto for engagement at opposite sides of 115 the container whereby to receive the clothes line within said U-shaped member and between said member and the container, and a reel mounted within the container around which the strip may be wound when not in 120 use.

6. A clothes line covering device including a reel, a strip of flexible material adapted to be wound upon the reel when not in use, and means for creasing the strip 125 longitudinally while said strip is being wound upon the reel.

7. A clothes line covering device includ-

ing a container having an opening, a reel
mounted within the container, a strip adapt-
ed to enter the opening of the container and
to be wound upon the reel, and a finger ex-
5 tending into said opening to crease the strip
as the same is being wound upon the reel.

In testimony whereof I affix my signature
in presence of two witnesses.

FLORENCE C. WASHBURN.
